G. A. CATHEY

GAS VALVE

Filed Feb. 3, 1925

INVENTOR

George A. Cathey.

BY
Albert E. Dietrich
ATTORNEY

UNITED STATES PATENT OFFICE.

GEORGE A. CATHEY, OF PORTLAND, OREGON.

GAS VALVE.

Application filed February 3, 1925. Serial No. 6,640.

To all whom it may concern:

Be it known that I, GEORGE A. CATHEY, a citizen of the United States, residing at Portland, in the county of Multnomah and 5 State of Oregon, have invented certain new and useful Improvements in Gas Valves, of which the following is a specification.

The invention generally relates to gas valves and has for its object to provide such 10 a valve as will automatically function to cut off the supply of gas to a burner when the pressure thereof falls below the pressure necessary to sustain the light of that burner, thereby preventing dangerous gas leakage.

15 With the above and other objects in view that will hereinafter appear the invention further resides in those novel details of construction first fully described in the following description, then particularly pointed 20 out in the appended claim, and illustrated in the accompanying drawing, in which:—

Figure 1 is a longitudinal section illustrating the invention.

Figure 2 is a plan view of the invention. 25 Figures 3 and 4 are cross sections taken on the lines 3—3 and 4—4 respectively.

In the drawing in which like numerals of reference indicate like parts in all the figures 30 1 represents a gas conduit pipe adapted to communicate between a source of gas supply and a burner. As the source of supply and the burner form no part of the invention illustration thereof is deemed unnecessary.

The conduit section 1 is constructed to include 35 a valve seat 2, adapted to accommodate the ball valve 3, movement of which is provided for in the housing extension 4, screw capped at 5, and the said valve and seat serve to divide the said conduit into a passage portion 6, in advance of the seat, and a passage portion 7, beyond the seat, the purpose for which will later appear.

A valve unseating lever 8 having an upturned ball engaging end 9 is pivotally 45 mounted in the passage portion 7 on the cross pin 10 mounted in the walls of the conduit 1. A pull rod 11 is secured to the lever at 12 and extends upwardly through a port 13 which communicates with the interior of the 50 diaphragm 14 secured to the conduit at 15. The diaphragm is suitably housed in the casting extension 16 which is suitably capped at 17 and ported as at 18 to communicate with atmosphere. The pull rod 11 is secured 55 to and passes through the top wall of the

diaphragm as at 19 and is extended through the air port 18 to provide a convenient hand hold.

The conduit section 1 may be end threaded as at 20 to facilitate its being spliced into 60 any gas conduit with which it is to cooperate for its designed purpose.

Those familiar with the use of gas burners have experienced that the pressure of the gas supplied thereto frequently falls below 65 that necessary to sustain the active condition of the burners. When this condition occurs the burners snuff out and the gas continues to leak out. The danger and waste occasioned by such a happening is obvious and 70 to provide a simply constructed valve device capable of automatically functioning to completely cut off the supply of gas when its pressure falls below that necessary to sustain the function of the burner is the purpose of this invention. 75

The operation of the invention is as follows. Assume the ball valve 3 to be normally seated by gravity and gas pressure in the passage portion 6, thus cutting off communication through the passage portion 7 to the burner. The pressures in the passage portion 7 and the chamber surrounding the diaphragm 14 are equal (atmospheric pressure) and the said diaphragm in its normal or collapsed condition, causing the rod 11 to force the end 9 of the lever 8 away from engagement with the ball 3. 80

The operator grasps the extended pull rod 11 and, by a pull thereof, distends the 90 diaphragm to cause the lever 8 to swing upwardly on its pivot so that the end 9 thereof will engage and unseat the ball valve 3, permitting communication of the passage portions 6 and 7. This accomplished, and 95 so long as the pressure of the gas remains sufficient to sustain the active condition of the burner, the gas pressure in the passage portion 7, communicating with the diaphragm 14 through the port 13, will sustain 100 the distended condition of that diaphragm and the positioning of the lever end 9 for preventing seating of the valve 3.

Should the gas pressure in the passage portions 6 and 7 decrease to a point where 105 the sustaining of active burner condition is impossible or unlikely (the diaphragm is sensitively constructed to provide for this) the diaphragm will, under atmospheric pressure, collapse to its normal condition 110

first mentioned and permit a seating of the valve 3 and the consequent complete cutting-off of gas supply.

From the foregoing description, taken in connection with the accompanying drawing, the novel details of construction, manner of operation and advantages of the invention will be apparent to those familiar with the uses to which the invention may be put.

What I claim is:

A device of the class described comprising a pipe-like conduit length threaded at its opposite ends to facilitate splicing into a gas conduit, a valve housing projecting from the upper walls of the conduit length and having a valve seat therein, a gravity actuated valve operable in the housing, a removable closure cap for the housing, a di-

aphragm housing projecting from a wall of said conduit length, a closure cap for the diaphragm housing having a port providing atmospheric communication thereinto, a hollow diaphragm in the diaphragm housing, said conduit length having a port leading into the diaphragm housing and said diaphragm being so mounted that that port communicates with the interior thereof, an actuator rod connected to a part of the diaphragm to be moved thereby when distended, and a pivoted lever to which said rod is connected and which is constructed and mounted to cause unseating of the valve against gravity action when the diaphragm is distended.

GEORGE A. CATHEY.
